CLAIM

We claim the ornamental design for a six-cell beverage box with top flaps, as shown and described.

DESCRIPTION

FIG. 1 is a rear perspective view of a six-cell beverage box with top flaps showing the claimed design with a top portion positioned in an open configuration and a telescoping portion positioned in an extended configuration.

FIG. 2 is a front elevation view thereof.

FIG. 3 is a rear elevation view thereof.

FIG. 4 is a left-side elevation view thereof.

FIG. 5 is a right-side elevation view thereof.

FIG. 6 is a top plan view thereof.

FIG. 7 is a bottom plan view thereof.

FIG. 8 is a plan view of the six-cell beverage box with top flaps shown in a fully collapsed configuration.

FIG. 9 is a top perspective view of the six-cell beverage box with top flaps shown with the top portion in the open configuration; and,

FIG. 10 is a front perspective view of the six-cell beverage box with top flaps with the telescoping portion positioned in a retracted position and the top portion in a closed configuration.

Those features shown in broken lines, such as the broken lines denoting lines of weakness shown in FIGS. 1, 4, 5, and 8, form no part of the claimed design.
